JOSEPH DE KORWIN, OF BRUSSELS, BELGIUM, ASSIGNOR TO KORWIN FLYER COMPANY, OF CHICAGO, ILLINOIS, A CORPORATION OF ILLINOIS

GYROSCOPE FLYING MACHINE WITH OSCILLATING WINGS

Application filed December 20, 1929, Serial No. 415,484, and in France August 27, 1929.

In all flying machines constructed up to date the lifting force is obtained through the action of the air on a surface under rectilinear propulsion as in the aeroplanes; or 5 through the rotation of vertically propelling driven surfaces, as in the helicopters; or, finally, through rotation of surfaces resulting from their longitudinal displacement at an inclination, under the influence of motive 10 traction, as in the autogyros.

These different systems all have disadvantages inherent in their very principles. The aeroplane cannot rise vertically. It cannot fly, that is, maintain itself in the air, except 15 on condition that it can maintain a sufficient horizontal speed.

The same is true, though in a smaller degree, with the autogyro. As for the helicopter, the problem of its stability does not 20 seem to have been solved as yet. The motoric torque necessary to cause its propeller to rotate in a horizontal plane tends to cause the apparatus as a whole to rotate in the opposite direction, and this necessitates using 25 several propellers, two at least, rotating in opposite directions, in which case the stabilizing gyroscopic torques of the apparatus are nullified, and the apparatus no longer has any proper stability.

It is true that complicated devices for stabilizing the machines have been conceived, but 30 these means are difficult to make, and they depend upon the control of the pilot, who can be led into error by atmospheric surroundings. Moreover, in case the motor 35 stops, these means likewise fail for lack of the power that is needed to operate them.

The apparatus forming the subject of the 40 present invention is based on the same principle as the flight of birds. It can be considered to be a machine with reciprocating wings, yet it embodies the advantages of the helicopter in this respect, that as the wings are set in movement the motion is circular, and flight can be sustained over a spot without any displacement of the center of gravity 45 of the machine.

Furthermore, in this flying machine the 50 supporting surfaces all rotate in the same direction, thus creating a gyroscopic mo-

mentum which gives to the whole machine a proper stability, which is maintained as long as the rotation is continued.

The machine utilizes aerodynamic surfaces which, in transverse section, have a 55 known profile paraboloid and are designed in such a manner as to give the best performance possible.

These surfaces are pivoted and each has imparted to it, through one of its ends, a free 60 circular movement around a vertical axis, and at the same time that it receives, from any suitable motive force, an alternating vertical movement of a predetermined amplitude. 85

One of the essential characteristics of this 70 invention is that these surfaces, which constitute in effect two sets of propeller blades, one above the other, receive their rotation solely from their alternating vertical strokes imparted by their motor.

The result of this condition is that the apparatus as a whole is in no manner subject to the reaction of the momentum of rotation, and that, consequently, all the surfaces can 75 rotate in the same direction, thereby producing a gyroscopic torque and insuring perfect stability to the flying machine.

In order to produce rotation through the influence of vertical movement, the blades are 80 movable around horizontal axes radiating from the vertical axle. On these horizontal axes the blades assume variable inclinations, according to whether they ascend or descend, and in principle, according to the position 85 that they occupy relatively to their course of flight.

These movements of inclination can be produced automatically through the choice of the 90 pivot points of the blades, or they can be controlled by a device forming part of the mechanism. In either case they can be subject to control of the pilot.

The attached drawings represent several 95 flying machines constructed on the principle of the present invention.

Figure 1 represents in elevation, the assembled apparatus including a single group of wings. 10.

Figure 2 shows the same in plan, with portions of two of the wings broken off.

Figure 3 is a vertical axial section, showing the mechanism during the descent of the 5 blades, and indicating the aerodynamic forces developed thereby.

Figure 4 represents the angular position of a wing during the ascent.

Figures 5 and 6 represent, by front elevational and plan views, a modified application of the principle, in which are employed 10 two groups of upper and lower wings arranged in multiple aspect.

Figure 7 is a detailed view of motion transmitting device used in Figures 5 and 6.

Figures 8 and 9 are, respectively, vertical sections in two planes at right angles to each other of means through which to impart, from each of the horizontal shafts of Figure 20 7, opposite oscillatory movements to the upper and lower groups of wings; and.

Figures 10 and 11 are, respectively, a side elevation with a portion of the fuselage in vertical section, and a top plan view with 25 two blades broken away and a portion of the fuselage in horizontal section showing the application to the machine of an independent dirigible motor and propeller through means of which horizontal propulsion may be imparted to the machine.

Referring to Figures 1 and 2, it will be seen that the carrying surfaces A1, A2, A3, and A4 are mounted upon the tubes B1, B2, B3, and B4, respectively, which latter are fitted 35 into the sockets C of the naves C1, C2. These naves, being mounted through means of anti-friction bearings, can turn freely around the sleeves D1, D2, which are, in turn, vertically slidable upon the column E. This column E rests with its lower end within a 40 cabin or fuselage F, where it is connected with wing-reciprocating mechanism operated by the motor G.

The whole machine, including the pilot's 45 cabin or fuselage, is supported by means appropriate to the medium upon which it is desired to have the machine alight, for instance, a landing gear typified by the four small wheels H upon which the machine may 50 travel.

The wing-reciprocating mechanism comprises, in addition to the motor G, a speed reducer I and a crank shaft J of large dimensions with three cranks keyed at 180° apart.

55 The central crank has a connecting rod K which, inside the column, operates the slide D1.

The two other cranks receive two connecting rods L1, L2, which actuate the slide D2.

60 The two slides D1, D2 thus receive similar movements but in reverse directions. They slide on the column E, one ascending while the other one descends, and vice versa.

The blades A1, A2, A3, A4, pivoted on 65 the tubes B1, B2, B3, B4, each carry in their

center a roller M which, when the blade is raised by the air, is able to bear against a cam or rolling path N, the position of which, in relation to the slides D1, D2, can be fixed once and for all or be changed while running, at the choice of the pilot, by means of suitable flexible or rigid controls.

In Figure 3 the blade A is in its descending position, its pivoting on the tube B being plainly ahead of the center of its course, 75 while its rear part rises and its roller M comes to bear against the rolling path N. In this position the aerodynamic reactions furnish, on the one hand, an upward force 1 and, on the other hand, a horizontal force 2, 80 and these tend to rotate the blade around the vertical column E.

It is evident that the intensity of the forces 1 and 2 depend upon the incidence of the wind relatively to the blade A, but this angle is 85 changed if one changes the position of the rolling path N on which the roller M rests.

This feature makes possible the maneuvering of the apparatus in the following manner:

90 By means of distance controls, either flexible ones or, more practically, by means of pneumatic, hydraulic or electric controls, the pilot can displace the rolling path N in relation to the slide B. For this purpose, the 95 rolling path N is connected to the slide B at three points by means of connections O of variable length.

By acting simultaneously on the three connections, the pilot can cause the rolling path 10 of the slide to recede or approach, which increases or diminishes the rotation of the supporting blades.

By acting unequally on the three connections, O, the pilot inclines the rolling path, 10 which causes the incidence of the blades to vary according to the positions they occupy in relation to the axis of the apparatus thereby creating unequal supporting action of the blades at different portions of their revolution; that is to say, developing a greater supporting force on one side of the machine as compared with the other side and tending to incline the column E away from the vertical. Thus the pilot is able to incline or straighten up the machine at will, either longitudinally or laterally. Particularly is he able to give it in advance an inclination which determines its horizontal displacement, or, on the contrary, brake this horizontal speed by inclining the machine rearwardly.

Figure 5 shows how the connecting rod K actuates the slide D through two diametrically opposed slots made in the central column E. This slide carries two sets of connecting rods on which the nave C can freely turn, in which the tube B is attached.

Figure 4 represents the blade during its ascending stroke. In this movement, the

blades of the wing take an incidence limited by the rollers M, or by any other suitable arrangement, and this incidence promotes rotation of the wing and the screwing of the blades into the air so that only slight resistance is encountered in the upward movement of the wing.

As will be understood, the crank shaft J imparts opposite reciprocations to the wing groups through means of the connecting rod K leading to the upper group, and the two connecting rods L1, L2 leading to the lower group. When there are four groups of wings, as shown in Figures 5 and 6, the engine G 10 will impart rotation to the vertical shaft K1 (Figures 5 to 7) which carries at its upper end the bevel gear K2 meshing with the two bevel gears K3, K4 on the horizontal shafts K5, K6, which horizontal shafts carry at 20 their outer ends, as shown in Figures 5 and 6, suitable arrangements Q, each of which may consist of Scotch yokes Q1, Q2, cooperating with eccentrics Q3, Q4 on each horizontal shaft; and these Scotch yokes Q1, Q2 25 are connected, respectively, by vertical rods Q5, Q6 with the outboard wing groups, namely, the upper outboard wing group A_{x1}, A_{x2} and lower outboard wing group A_{x3}, A_{x4} on the one side in Figures 5 and 6, and the 30 upper outboard group A_{y1}, A_{y2} and lower outboard group A_{y3}, A_{y4} on the other side in said figures.

As shown in Figures 10 and 11, the machine in either of the forms herein illustrated may 35 be provided with an independent engine through means of which to obtain more rapid horizontal propulsion than is obtainable by merely inclining the rolling path N, as previously described. And this auxiliary engine 40 with its propeller will preferably be so supported, for instance, upon the pivoting and trunnioning mounting S, that by manipulation of the handles T it may be traversed in a horizontal plane in a manner to develop 45 very sudden changes in direction of flight, thereby rendering the machine very advantageous in warfare, as by reducing to a minimum the possibility of being shot down by anti-aircraft guns; the trunnioning of the 50 mounting also permitting changes in angle of elevation or depression of the axis of the propeller in a manner to assist greatly in changing the course of the machine in vertical planes.

55 From the foregoing it will be seen that the vertical reciprocating motion imparted to the blades causes a rotatory movement of these blades at the same time that it develops supporting effort. On the other hand, as the 60 blades are free to rotate around the vertical axle, they produce no torque tending to make the machine rotate. Finally, the support obtained through all the blades jointly, of which some rise while the others descend, is 65 regular and constant.

The rotating of all the blades in the same direction forms a gyroscope and maintains the stability of the apparatus.

In the application of the invention described above by way of example, the reciprocating movement is transmitted from the motor to the wings by means of a mechanical arrangement of rods and levers, but it would just as well be obtained through hydraulic or pneumatic transmission by means of pistons and cylinders in which the fluid plays the role of transmitting agent or by any other means of transforming a continuous rotary movement into an alternating rectilinear movement. Every device accomplishing this 75 end can be applied to the carrying out of the idea of the invention and falls within the scope of the same.

To recapitulate, the present invention contemplates a flying machine having autorotative reciprocating wings.

The vertical ascent is obtained through the alternating movement of aerodynamic surfaces pivoted in such a manner that the reciprocating movement produces a rotatory 90 movement of the surfaces around a vertical axle.

Two sets of blades moving vertically in opposite directions but rotating in the same direction.

Movement is imparted to the wings by a set of rods and levers operated by a motor or by any other mechanical means or any electric, hydraulic or pneumatic means.

Mechanical devices control the inclination 100 of the blades in such a manner that air is encountered by the main surface of the blades in their downward strokes, but only by the edges of the blades in their upward strokes.

The inclination of the blades during the 105 descending movement can be varied and modified by the pilot during the flight, for the purpose of directing the machine or changing its speed, or both.

Automatic rotation of the blades during 110 descent of the machine provides a slow and safe landing in case the motive power fails.

The movement of the wings through the air prevents accumulation of ice and snow 115 and avoids adding to the weight of the machine while flying under bad weather conditions.

I claim:

1. A flying machine having a wing reciprocating on an approximately vertical axis, and 120 constructed with surfaces which, under such reciprocating movement react to develop rotation of the wing in a plane substantially perpendicular to said axis; said wing being supported with freedom to revolve in response to said reaction.

2. A flying machine having a wing reciprocating on a substantially vertical axis approximately perpendicular to the plane of 125 the wing; said wing being constructed with 130

- surfaces that react from each direction of such reciprocating movement to develop rotation of the wing in the plane of the wing, and the wing being mounted with freedom to rotate under said reaction.
5. A flying machine having reciprocating wings pivotally mounted with freedom to present their edges to the air in their upward movement and present broad faces to the air in their downward movement, said wings being mounted so that they will also be free to move in a plane perpendicular to the direction of their reciprocating movement.
4. In a flying machine, reciprocating wings, pivotal supports for said wings permitting them to change their angles of incidence relatively to the air during their upward and downward movements, and means carrying said pivotal supports with freedom to rotate about a vertical axis.
- 15 5. In a flying machine, reciprocating wings, pivotal supports for said wings permitting them to change their angles of incidence relatively to the air during their upward and downward movements, means carrying said pivotal supports with freedom to rotate about a vertical axis, and means limiting the pivotal action of the wings during their downward movement and to cause them to present their major faces to the air.
- 20 6. In a flying machine, reciprocating wings, pivotal supports for said wings permitting them to change their angles of incidence relatively to the air during their upward and downward movements, means carrying said pivotal supports with freedom to rotate about a vertical axis, and means limiting the pivotal action of the wings during their downward movement and to cause them to present their major faces to the air; the last-named means being adjusted to permit said major faces of the wings to assume an angle greater than a right angle to the direction of downward movement, and thereby develop a reaction in the wings which causes them to travel about the said vertical axis.
- 25 7. In a flying machine, a series of radial wing supports, means for imparting vertically reciprocating movement to said wing supports, wings pivotally mounted on said supports with freedom to yield under the reaction of the air and present their minor dimensions to the resistance of the air during upward movement of the wings, and means arresting the pivotal action of the wings during their downward movement and causing them to present their major faces during said downward movement; the last-named means being adjustable to change the angle of presentation of the wings.
- 30 8. A flying machine as described in claim 1, in which the wing is composed of a plurality of blades arranged approximately radially to the axis of reciprocation, and each movable under the reaction of reciproca-
- tion to the position which develops the reaction in the rotary direction.
9. A flying machine as described in claim 1, in which the wing comprises a plurality of blades arranged approximately radially to the axis of reciprocation of the wing, individually movable under the reaction of each direction of reciprocation to positions which present their surfaces at angles of incidence that develop the reaction in the rotary direction of the wing; the angle of incidence assumed by the blades during one direction of reciprocation being materially less than in the other direction.
- Signed at Chicago, Illinois, this 5th day of December, 1929.
